REMOTE CONTROL STRIP STAMP DISPENSING DEVICE

Carl J. Crane, Helotes, Tex., assignor to Charles M. Masser and Britt Moore, both of San Antonio, Tex.

Filed Apr. 18, 1960, Ser. No. 22,961

5 Claims. (Cl. 226—135)

This invention relates to a mechanism for dispensing sheets of strip material and more particularly to a device for dispensing stamps, tickets or other items that may be printed on long strips of paper whose operation may be controlled from a remote point.

This invention is an improvement on the Strip Stamp Dispensing Device disclosed in the application of Britt Moore and Carl J. Crane, Ser. No. 843,134, filed September 29, 1959, now abandoned.

Many different types of stamp dispensing or ticket dispensing mechanisms have been designed and built. In general, the primary aim of all such mechanisms is to provide a controlled drive mechanism that will move the desired number of units to a given cut-off point so that the separate units, whether they are tickets, stamps or other similar items may be presented to a customer or other person utilizing said units.

While the mechanism described in this invention may be used to dispense admission tickets and the like, the present invention has been particularly designed to dispense merchandise stamps of the type now distributed by many stores as a bonus or participation dividend for customers. In accordance with the present merchandising practice where stamps of this nature are utilized, it is customary to give the number of stamps for each purchase that corresponds to the number of basic money units that are represented by such purchase. For example, if a stamp is to be given for each dime or ten cents spent, the purchaser of a dollar item should receive ten stamps. At present the stamps used for this purpose are removed from a sheet supply of stamps by hand and presented to the customer. Through long experience, it has been found that this hand method of dispensing merchandising stamps is a very bothersome and time consuming practice.

The present invention is an improvement over all other stamp dispensing devices, in that it has the unique feature of being controlled from a remote point. In other words, the selector unit is merely connected to an actuating mechanism by an electric conduit which may have any practical length. It will be understood, of course, that the remote control assembly may be mounted on the same chassis as the stamp containing device.

It is therefore a primary object of the present invention to provide a stamp dispensing device whose operation may be controlled from a remote point.

It is another object of the present invention to provide a remotely controlled stamp dispensing device which will automatically dispense the required number of stamps for each purchase.

It is still another object of the present invention to provide a remotely controlled stamp dispensing device having provision for receiving and holding a considerable number of stamps.

It is yet another object of the present invention to provide a remotely controlled stamp dispensing device having a first selector and drive mechanism intercon-

2

nected to dispense a desired number of single strip stamps and a second selector and drive mechanism adapted to dispense the required number of stamps in ten unit groups.

5 Additional objects and advantages of the present invention will be apparent from the appended description and drawings in which:

Figure 1 is a fragmentary perspective view showing the device of the present invention;

10 Figure 2 is a side view of the device taken along lines 2—2 of Figure 4.

Figure 3 is a diagrammatic layout of the electric circuitry necessary to the operation of the present invention.

15 Figure 4 is a rear view fragmentary section of the device.

Figure 5 is a top view of the remote control assembly.

Figure 6 is a side view of the remote control assembly.

Figure 7 is a side view of the switching mechanism.

20 In the following detailed consideration of the invention only one side of the device will be described. Both the stamp dispensing unit which distributes stamps in accordance with dollar unit purchases and the stamp dispensing unit which distributes stamps in accordance with fraction of a dollar purchases are identical in their stamp 25 actuating mechanism, the chief difference being in that the dollar unit dispenses a sheet of stamps consisting of two rows of five stamps each, for each dollar, while the fraction of a dollar side merely dispenses one stamp for each ten cents unit.

30 Now, turning to the drawings for an elucidation of the invention, Figure 1 discloses the instant device with its cover removed in a fragmentary manner and is a perspective view. The device is secured to a base 11. The mechanism is mounted between upright 12 and upright 35 13 which are perpendicular to the base. Another perpendicular upright 14 is secured to the base and separates the stamp roll 15 containing zone from the actuating mechanism zone.

35 The actuating mechanism is solenoid operated. The 40 solenoid 16 is keyed into operation from a remote station through an electric conduit 17 shown in Figure 3. The remote station assembly, generally 18, is shown in Figures 5 and 6 about which more will be said later. Of course, it will be readily understood that the remote 45 station assembly may be mounted on the same chassis as the stamp roll and stamp actuating mechanism.

The stamp roll is mounted on a shaft 19 which has two annular slots 20 which slides into cut channels 21 in the partitioning upright 14 and in one end upright 13. 50 A U-shaped clip 22, having spaced ears 23 along the bottom of the connecting portion of the clip, serves to guide the unreeeling of the stamp strip. A threaded rod 24 passes through suitable openings in uprights 13 and 14 and suitable openings in the spaced ears 23. The 55 rod is secured by pin 25 and knurled knob 26. The opening in one of the ears is threaded as is the corresponding portion of the rod 24 which passes therethrough so that the U-shaped clip may be moved horizontally thereby displacing the stamp roll and aligning 60 it with the feed rolls.

The stamp strip 15 is run over idling roller 27 which is mounted between uprights 13 and 14. A driven spool 28 is positioned in back of and parallel to the idling roller 27 (as in Figure 4). The spool has four pairs of 65 equally spaced pins 29A perpendicular to the periphery of the spool. The pins are spaced suitably so as to engage the perforations between the stamps thereby propelling them. The stamp strip after passing over idling 70 roller 27 is run along the underside of spool 28 between it and three vertical guide plates 29. These guide plates are an extension of rod assembly 30 (as seen in Figure 2)

which forms the lower portion of the discharge gate. The rod assembly is constructed of a number of bored annular segments between which guide plates 29 are positioned. The entire assembly is secured between uprights 13 and 14 by bolt 31. The stamp strip is passed from the underside of the spool 28 to the uppermost side of the rod assembly. In order that the pins 29 smoothly release the stamps, additional guide plates 32 are positioned and secured along rod 33 which is mounted between the uprights 13 and 14. Guide plates 32 curve over a portion of the upper periphery of rod assembly 30 and end in a depending point which is located within a portion of an annular groove 33 in spool 28, corresponding in number to the number of guide plates 32, thereby lifting the oncoming stamp strip away from the spool 28 and directing it out the gate. The upper portion of the gate consists of a cutting bar 36 having a plurality of serrations and being secured by screw 34 to a strip 35 which is secured to the edges of guide plates 32.

In order to insure a proper fit and positioning of the perforated portion of the stamps with respect to the tear off gate after each run of the spool, the spool 28 is controlled by means of a sprocket flange 40 which is secured to the end of the spool and turns therewith. Flange 40 has a plurality of detents 41. In the case of the spool shown where ten stamps are dispensed for each dollar, the number of detents required is two, each being 180° apart. In other words, the circumference of the spools in both instances is a dimension corresponding to the length of four stamps. In the cents spool, four detents are required since only one stamp is dispensed at a time. A cam roller follower 42 rides on the flange and drops into the detents. The follower is fitted to one end of a rocker shaft 43 which has its other end pivotally secured to vertical upright 13. The spring 44 attached to the rocker shaft 43 and upright 13 urges the follower 42 downwardly. From Figure 4 it is seen that the rocker 43 is located on one side of upright 13, while the roller follower is on the other. A suitably dimensioned slot in upright 13 provides operative freedom of movement therebetween.

The spool 28 has a shaft 37 which extends through the upright 14 into the actuating zone described between uprights 12 and 14. It ends in a slot arrangement 45 into which a tongue 46 extends. Free play is provided between the two so that there may be approximately 10° movement, thus permitting the spool 28 to accommodate the proper stamp alignment. Tongue 46 is connected to shaft 47 which is driven by motor 48 through a suitable clutch mechanism (not shown). The motor 48 is provided with an integral clutch mechanism which frees the rotating armature as soon as power is interrupted. The motor shaft has a knurled knob 48A by which the mechanism may be hand rotated to assist in the threading operation. The motor is geared so that the shaft 47 rotates about 70 r.p.m. to drive the stamp spool 28 by means of shaft 37. A small gear 49 is fixedly mounted concentrically on shaft 47 and is positioned to mesh with large gear 50. Large gear 50 has a micro switch 51 secured to one flat surface thereof. The other side of the gear 50 carries a non-conducting tubular portion or hub 52 on which slip rings 53 and 54 are concentrically secured. Suitable leads 55 connect the microswitch 51 through an opening in gear 50 to the slip rings 53 and 54. Suitable brushes 56 and 57 slide on the slip rings. The brushes are clamped between non-conducting blocks 58 which in turn are secured to upright 60 which is mounted on base 11. Suitable lead wires (not shown) supply line voltage to the brushes.

A shaft 61 is mounted concentrically with gear 50 and its assembly. It is mounted between pin bearing 62 and adjustable pin bearing 63. A ratchet wheel 64 is fixedly mounted on shaft 61. The ratchet wheel is in operative relationship with pawl 65 which is also the reciprocating

armature of the solenoid 16. The pawl 65 is urged upwardly by spring 66 which has one end attached to an ear 67 on the motor housing and its other end attached to the pawl (as in Figure 2). U-shaped member 68 has its connecting portion passing through slot 70 in the pawl 65. This member acts as a stop for the pawl. A star wheel 71 with ten detents is an integral part of the ratchet wheel 64 and rotates with it. A rocker arm 72 has a roller 73a at one end thereof which engages the star wheel 71 in order to position the shaft 61 accurately. The rocker arm 72 is pivoted about the connecting portion of U-shaped member 68. The other end of the rocker arm is spring loaded downwardly by means of a spring 73 which is attached to the rocker arm and to an ear 74 secured to the solenoid housing 16.

A conventional spring loaded ratchet type counter arrangement 80 is mounted near the top of upright 12. The counter arm 81 is tripped by rocker arm 82 which is pivoted about pin 83 mounted perpendicularly to upright 12. The extending arm 84 is the driven arm which engages the L-shaped driving arm 85 which is mounted into shaft 61. Each rotation of shaft 61 moves the counter one digit connoting the ejection of ten dollar equivalent of stamps.

A switch cam 90 is fixedly mounted on the shaft 61 on the same side of the large gear 50 as the microswitch 51. From Figure 7 it will be noted that the microswitch 51 has a cam follower 91 which opens the microswitch when it rides into cam depression 92. The microswitch 51 is in series with one lead to the motor so that when the switch is open, the motor is de-energized.

Now turning to Figures 5 and 6 for a detailed discussion of the remote control assembly, attention is directed in particular to Figure 6 which shows the side view of the assembly with its cover 101 removed. A timing belt 102 is secured about idling pulley 103 and sprocket pulley 104. The timing belt 102 is fitted with a plurality of finger tabs 105. These tabs project through slots 106 along the upper surface of the cover 101. The slots are separated by a strip 107 on which is imprinted by a suitable manner the numerals 1 to 10 which serve as the keyboard reference for dollar and dime selections. The symbol dollar sign and cent sign are marked adjacent the lamp holes 110.

The pulleys are mounted on suitable axles 108 which are secured through center keel support plate 109. The axles may extend beyond the other side to accommodate a like pulley arrangement for the other timing belt. One timing belt is for the dollar side and the other is for the cents side. The mechanism for each is identical. The timing belt 102 and its associated finger tabs must remain in phase with the sprocket pulley 104 in order that cam 111 which is mounted on the face of the sprocket pulley will properly time the action of the switch 112. The cam 111 serves a dual purpose of actuating the switch 112 as well as holding the timing belt in proper position with tab interval opposite the selection numerals when the belt is at rest. The spring 113, its bracket support 114 and the lever 115 cooperate to maintain pressure of the cam follower 116 onto cam 111. Electric conduits 117 and 118 serve the switch 112 having contacts 119 and 120. The lever 115 is equipped with insulating bushings at the fulcrum pin 121, at the cam follower, and at the spring hole 122 in order to prevent grounding.

A lamp 125 is provided beneath each of windows 110 so that when motor 48 is energized, the light is also energized. Suitable electric leads are provided between the remote control assembly and the lead line to the motor to energize both when microswitch 51 is closed.

The side of the remote control assembly shown in Figure 6 is the cents side. However, the other side, as has been stated, is the same. Housing cover 101 is retained by screws 126. A normally closed limit switch 130 is provided proximate the stamp roll, shown in Figures 2 and 3. The limit switch is made up of lever 131 having a cam

portion 132 and contacts 133 and 134 which are opened when the roll is depleted by the action of spring 135 which is secured to the base 11 and lever 136. This latter lever is coupled to the cam lever 131 by rigid shaft 137, seen in Figure 4. The parts of the switch are isolated from the rest of the device by suitably positioned insulating bushings.

The gear ratio of gear 49 and gear 50 is 1:5. One complete revolution of the spool 28 ejects 4 linear stamps; hence 20 linear stamps are required for a ten dollar demand. It follows that five revolutions of the spool 28 are required to one revolution of the large gear.

In operation, the switch 112 is operated from 1 to 10 times with one hand movement. This switch operation in the remote control assembly will cause the mechanism to eject from 10 to 100 stamps, respectively, if the left side (dollar) timing belt is used. If the right side (cents) switch is actuated, from 1 to 10 stamps will be ejected. Accordingly, if for instance, a purchase is made for a total of \$4.35, this amount is entered in the remote control assembly by first placing a finger in between the finger tabs to the left of the numeral 4 on the assembly, and then pulling the tab down to the stop 140. This will cause 40 stamps to be ejected. Then the finger is placed in between the finger tabs to the right of the numeral 3 on the assembly and by then pulling the tab down to the stop 140, three stamps will be ejected.

If the finger tab is used to enter either one dollar or one dime input, then one switching contact is made on either the dollar or the cent switch. One switching contact at switch 112 will cause the solenoid 16 to be energized once. This will operate the pawl 65 and ratchet wheel 64 to rotate the cam 90 counter clockwise a distance equal to $\frac{1}{10}$ of a complete revolution. Immediately the switch 51 closes contacts to energize the motor 48. The motor running drives directly the stamp spool 28 which draws stamp material from the roll 15 thru the gate for a linear length of two stamps for a total of 10 stamps. At the instant this stamp material is ejected, the switch 51 contacts are opened again and the mechanism stops. The small gear 49 rotates with the motor and spool drive shaft 37. It engages the large switch gear 50 which carries the lever operated switch 51 along until its lever cam follower 91 drops into the cam depression 92, thusly opening the switch and de-energizing the motor 48. If the tab representing ten dollars is pulled causing the switch 112 to make 10 contacts, then the solenoid 16 will function 10 times which will rotate the cam 90 one complete revolution. As the motor operates to dispense 100 stamps (20 linear) the large gear 50 and its switch will rotate as shown in Figure 3 until the large gear 50 and its integral switch 51 return to the off position shown. The lamp will light as long as the mechanism is running. If more than 10 dollars' input to the assembly is contemplated, the excess over 10 dollars such as 7 must be inserted into the assembly after the first 10 dollar run of stamps has been ejected. The warning lamp remains lighted until the mechanism stops. The switch 130 remains closed as shown in Figure 3 during all normal operation. However, this double-throw snap switch will operate to the alternate circuit thru conductor 124 to keep the lamp 125 continuously lighted when the stamp roll is nearly depleted. The lever 131, thru its associated cam 132, operates the switch 130. The lever 131 itself bears against the stamp roll 15, being urged into contact by means of the spring 135.

A cover 139, as seen in Figures 2 and 4, provides protection of the device from dust and tampering, and may be locked onto the base 11 by suitable means, if desired. The window of the counter 80 faces upwardly as shown in Figure 1.

It will be apparent that many changes and modifications of the several features described herein may be made without departing from the spirit and scope of the invention. It is therefore apparent that the foregoing description is

by way of illustration of the invention rather than limitation of the invention.

What is claimed is:

1. In a remote controlled stamp dispensing device having an actuated mechanism comprising a housing, a base within said housing, support members mounted on said base, a solenoid on said base, said solenoid having a reciprocating armature, a shaft mounted on said support members, a ratchet mounted on said shaft, said armature adapted to turn said ratchet one-tenth of a revolution for each stroke of the armature as the solenoid is energized, a cam wheel having a cam depression mounted on said shaft and adapted to rotate therewith, a first gear mounted concentrically around said shaft having independent rotation thereabout, an electric switch mounted on the surface of said first gear, said switch having a cam follower adapted to ride on said cam wheel, said switch being opened when the cam follower rides into said cam depression, an electric motor, said switch being in series with said motor, said motor driving a shaft, said shaft driving a second gear which is in engagement with the first gear, said shaft also driving a stamp draw spool mounted on said support members, means for carrying a stamp roll supply and gate means associated with said draw spool 25 through which stamps are ejected.
2. In a remote controlled strip stamp dispensing device having an actuated mechanism comprising a housing, a base within said housing, three spaced supporting uprights mounted on said base defining an actuating zone and a stamp containing zone, said actuating zone including a solenoid, said solenoid having a reciprocating armature, a shaft mounted in said actuating zone between two of the uprights, a ratchet mounted on said shaft, said armature adapted to turn said ratchet one-tenth of a revolution for each stroke of the armature as the solenoid is energized, a cam wheel having a cam depression mounted on said shaft and adapted to rotate therewith, a first gear mounted concentrically around said shaft having independent rotation thereabout, an electric switch 30 mounted on the surface of said first gear, said switch having a cam follower adapted to ride on said cam wheel, said switch being opened when the cam follower rides into said cam depression, an electric motor, said switch being in series with said motor, said motor driving a shaft, said shaft driving a second gear which is in engagement with the first gear, said shaft also driving a stamp draw spool positioned in said stamp containing zone, means for carrying a stamp roll supply and gate means associated with said draw spool through which 35 stamps are ejected.
3. In a remote controlled strip stamp dispensing device having an actuated mechanism comprising a source of electric pulses, a housing, a base within said housing, three spaced supporting uprights mounted on said base defining an actuating zone and a stamp containing zone, said actuating zone including a solenoid adapted to be supplied with electric pulses from said source, said solenoid having a reciprocating armature, a shaft mounted in said actuating zone between two of the uprights, a ratchet mounted on said shaft, said armature adapted to turn said ratchet one-tenth of a revolution for each stroke of the armature as the solenoid is energized, a cam wheel having a cam depression mounted on said shaft and adapted to rotate therewith, a first gear 40 mounted concentrically around said shaft having independent rotation thereabout, an electric switch mounted on the surface of said first gear, said switch having a cam follower adapted to ride on said cam wheel, said switch being opened when the cam follower rides into said cam depression, an electric motor, said switch being in series with said motor, said motor driving a shaft, said shaft driving a second gear which is in engagement with the first gear, said shaft also driving a stamp draw spool positioned in said stamp containing zone, means for carrying a stamp roll supply and gate means associated with said draw spool through which 45 stamps are ejected.
4. In a remote controlled strip stamp dispensing device having an actuated mechanism comprising a source of electric pulses, a housing, a base within said housing, three spaced supporting uprights mounted on said base defining an actuating zone and a stamp containing zone, said actuating zone including a solenoid adapted to be supplied with electric pulses from said source, said solenoid having a reciprocating armature, a shaft mounted in said actuating zone between two of the uprights, a ratchet mounted on said shaft, said armature adapted to turn said ratchet one-tenth of a revolution for each stroke of the armature as the solenoid is energized, a cam wheel having a cam depression mounted on said shaft and adapted to rotate therewith, a first gear 50 mounted concentrically around said shaft having independent rotation thereabout, an electric switch mounted on the surface of said first gear, said switch having a cam follower adapted to ride on said cam wheel, said switch being opened when the cam follower rides into said cam depression, an electric motor, said switch being in series with said motor, said motor driving a shaft, said shaft driving a second gear which is in engagement with the first gear, said shaft also driving a stamp draw spool positioned in said stamp containing zone, means for carrying a stamp roll supply and gate means associated with said draw spool through which 55 stamps are ejected.
5. In a remote controlled strip stamp dispensing device having an actuated mechanism comprising a source of electric pulses, a housing, a base within said housing, three spaced supporting uprights mounted on said base defining an actuating zone and a stamp containing zone, said actuating zone including a solenoid adapted to be supplied with electric pulses from said source, said solenoid having a reciprocating armature, a shaft mounted in said actuating zone between two of the uprights, a ratchet mounted on said shaft, said armature adapted to turn said ratchet one-tenth of a revolution for each stroke of the armature as the solenoid is energized, a cam wheel having a cam depression mounted on said shaft and adapted to rotate therewith, a first gear 60 mounted concentrically around said shaft having independent rotation thereabout, an electric switch mounted on the surface of said first gear, said switch having a cam follower adapted to ride on said cam wheel, said switch being opened when the cam follower rides into said cam depression, an electric motor, said switch being in series with said motor, said motor driving a shaft, said shaft driving a second gear which is in engagement with the first gear, the ratio of the first gear to the second gear being 5:1, said shaft also driving a stamp draw spool positioned in said 65 stamp containing zone, means for carrying a stamp roll supply and gate means associated with said draw spool through which stamps are ejected.
6. In a remote controlled strip stamp dispensing device having an actuated mechanism comprising a source of electric pulses, a housing, a base within said housing, three spaced supporting uprights mounted on said base defining an actuating zone and a stamp containing zone, said actuating zone including a solenoid adapted to be supplied with electric pulses from said source, said solenoid having a reciprocating armature, a shaft mounted in said actuating zone between two of the uprights, a ratchet mounted on said shaft, said armature adapted to turn said ratchet one-tenth of a revolution for each stroke of the armature as the solenoid is energized, a cam wheel having a cam depression mounted on said shaft and adapted to rotate therewith, a first gear 70 mounted concentrically around said shaft having independent rotation thereabout, an electric switch mounted on the surface of said first gear, said switch having a cam follower adapted to ride on said cam wheel, said switch being opened when the cam follower rides into said cam depression, an electric motor, said switch being in series with said motor, said motor driving a shaft, said shaft driving a second gear which is in engagement with the first gear, the ratio of the first gear to the second gear being 5:1, said shaft also driving a stamp draw spool positioned in said 75 stamp containing zone, means for carrying a stamp roll supply and gate means associated with said draw spool through which stamps are ejected.

stamp containing zone, said stamp spool having a circumference equal to four linear stamps, means for carrying a stamp roll supply and gate means associated with said draw spool through which stamps are ejected.

4. In a remote controlled strip stamp dispensing device having an actuated mechanism comprising a source of electric pulses, a housing, a base within said housing, three spaced supporting uprights mounted on said base defining an actuating zone and a stamp containing zone, said actuating zone including a solenoid adapted to be supplied with electric pulses from said source, said solenoid having a reciprocating armature, a shaft mounted in said actuating zone between two of the uprights, a ratchet mounted on said shaft, said armature adapted to turn said ratchet one-tenth of a revolution for each stroke of the armature as the solenoid is energized, a cam wheel having a cam depression mounted on said shaft and adapted to rotate therewith, a first gear mounted concentrically around said shaft having independent rotation thereabout, an electric switch mounted on the surface of said first gear, said switch having a cam follower adapted to ride on said cam wheel, said switch adapted to be opened when the cam follower rides into said cam depression, an electric motor, said switch being in series with electric conduits supplying said motor, said motor driving a shaft, said shaft driving a second gear which is in engagement with the first gear, the ratio of the first gear to the second gear being 5:1, said shaft also driving a stamp spool positioned in said stamp containing zone, said stamp spool having a circumference equal to four linear stamps, means for carrying a stamp roll supply, gate means associated with said draw spool through which a stamp strip is ejected, means for aligning said stamp strip with said gate including pin means mounted perpendicularly on said spool to engage the stamp strip, guide means to feed the strip to the spool and means for positioning the spool.

5. In a remote controlled strip stamp dispensing device having an actuated mechanism comprising a source of electric pulses, a housing, a base within said housing,

three spaced supporting uprights mounted on said base defining an actuating zone and a stamp containing zone, said actuating zone including a solenoid adapted to be supplied with electric pulses from said source, said solenoid having a reciprocating armature, a shaft mounted in said actuating zone between two of the uprights, a ratchet mounted on said shaft, said armature adapted to turn said ratchet one-tenth of a revolution for each stroke of the armature as the solenoid is energized, a cam wheel having a cam depression mounted on said shaft and adapted to rotate therewith, a first gear mounted concentrically around said shaft independently thereof to give rotation thereabout, an electric switch mounted on the surface of said first gear, said switch having a cam follower adapted to ride on said cam wheel, said switch adapted to be opened when the cam follower rides into said cam depression, an electric motor, said switch being in series with electric conduits supplying said motor, said motor driving a shaft, said shaft driving a second gear which is in engagement with the first gear, the ratio of the first gear to the second gear being 5:1, said shaft also driving a stamp spool positioned in said stamp containing zone, said stamp spool having a circumference equal to four linear stamps, means for carrying a stamp roll supply, gate means associated with said draw spool through which a stamp strip is ejected, means for aligning said stamp strip with said gate including pin means mounted perpendicularly on said spool to engage the stamp strip, guide means to feed the strip to the spool and means for positioning the spool, said source of electric pulses including a switch having electric contacts, a rotatable cam, a cam follower therefor, one end portion having means for riding said cam, the other end portion having means to periodically open and close said contacts in response to rotation of said cam.
